IGNITION SYSTEM

Walter E. Sargeant, Ferndale, Mich., assignor to
 General Motors Corporation, Detroit, Mich., a
 corporation of Delaware

Application August 8, 1941, Serial No. 405,952

11 Claims. (Cl. 123—148)

My invention relates to ignition systems of the type used in internal combustion engines.

With recent tendencies to increase the speed of internal combustion engines, some difficulty has been experienced with the timing of the spark. Also, where more current has been required it has been found necessary to supplement the existing ignition system by another similar independent system because of the difficulty of making parallel contactors operate simultaneously. But even where independent parallel systems have been used, some difficulty has been experienced in securing simultaneous operation of the two systems. Considerable difficulty has also been experienced in securing interrupter points which would stand up under the severe arcing existing in present ignition systems.

It is the object of my invention to overcome the aforesaid disadvantages of existing ignition systems by utilizing an electric valve, such as a grid controlled vacuum tube, to break the primary circuit of the transformer. A contactor is used to control the grid circuit. The grid circuit is always a low ampere circuit and there is little wear on the contactor points because of the decreased tendency to arc.

Figure 1 of the accompanying drawings is a circuit diagram of an ignition system embodying my invention.

Figures 2, 3 and 4 are graphs in which time is plotted against plate circuit current, plate voltage, and grid voltage, respectively, for one complete ignition cycle.

In the ignition system shown in the drawings 4 indicates a suitable source of electrical energy. Where the energy source is an ordinary 6-volt battery, I have found it necessary to use means to increase the voltage, such as a converter. Numerous converters are available which might serve the purpose of my system. I have found that a D. C. supply of 110 volts gives satisfactory operation.

A transformer is designated generally by 6. This transformer has primary and secondary windings 8 and 10 respectively. An electric valve or a number of electric valves connected in parallel, such as three-electrode vacuum tubes 12, are shown. I have found so-called "hard vacuum" tubes with grid control satisfactory. These tubes may be the same as high vacuum three-electrode tubes ordinarily used in radio receiving sets, except that I have found it necessary to strengthen the insulation of the lead-in wires. The tubes are similar to those used as class B amplifiers, such as RCA type 6A6. The plates or

anodes 14 are connected directly to one terminal of the primary winding 8 and the cathodes 16 are connected to the negative side of the principal power source. The positive lead from this power source is connected to the other terminal of the primary coil. A battery 18 is provided to heat the cathodes 16.

Control grids 20 are connected with an auxiliary primary winding 22. An interrupter or contactor 24 connects coil 22 with the positive side of the principal power source. A resistor 26 in this circuit serves to keep current flow through the grid circuit low as compared to the plate circuit.

Also connected to auxiliary coil 22 is a source of negative voltage such as battery 28. Battery 28 is connected to coil 22 through a filter circuit comprising resistance 30 and capacitance 32. By incorporating auxiliary winding 22 in my ignition system, I have found a negative bias of 22 or 23 volts satisfactory.

Secondary winding 10 is connected to a distributor 34 from which suitable leads or conductors go out to spark plugs 36. I have illustrated four plugs connected to a four-point distributor such as would be used in a four cylinder engine. In practice, of course, these plugs would be connected to the other side of coil 10 through a common ground. For the sake of convenience I have shown a direct wire connection.

The inductances, resistances, and capacities necessary to an operative ignition system embodying my invention are not critical. I have found that the following values give satisfactory performance: for winding 8 of the transformer, 1700 turns of No. 21 wire having an inductance of .6 henry and a resistance of approximately 14 ohms; for winding 10 of the transformer, 17,000 turns of No. 38 wire having an inductance of 60 henrys and a resistance of approximately 2500 ohms; and for winding 22, 200 turns of No. 30 wire having .01 henry inductance, and approximately 10 ohms resistance. Resistance 26 should have a value in the vicinity of 1000 ohms. Resistance 30 should have a value of approximately 5000 ohms. Condenser 32 should have a capacity of approximately .01 microfarad. The operation of my ignition system is as follows: With the contacts of interrupter 24 closed, a positive voltage bias is applied to control grids 20 which serves to make the tubes 12 conductive. A current builds up slowly through primary windings 8 and 22 so that there is insufficient rate of change in the magnetic field established by these primary windings to cause sparking of any of the plugs. At

the appropriate point in the cycle, which is determined by a suitable timing mechanism, the contact points of interrupter 24 are opened. Control grids 20 are thereby disconnected from the positive side of the principal power source, and are immediately effectively connected to the negative side of battery 28. The positive voltage applied to coil 22 is therefore rapidly reversed. Viewed in greater detail, it is seen that a small increment of change in voltage from positive to negative on the grid causes a change in the flux of winding 22, and therefore transformer 6, which necessarily affects winding 8. The resulting change in flux in winding 8, operating through the flux-linkage of transformer 6, affects winding 22 to still further decrease the voltage on winding 22 and to still further collapse the field. This "feed-back" characteristic results in a rapid reduction of the voltage on grids 20. In fact, because of the feed-back, a voltage surge occurs which is considerably greater in magnitude than the voltage of battery 28. It is this feed-back characteristic which makes it possible to use a battery of rather small potential at this point in the system.

The previously described collapse of the magnetic field in the primary windings induces a large voltage in secondary winding 10, which causes a spark to jump across the gap of the spark plug in the distributor circuit at that time.

What happens in the tube circuits of my ignition system is perhaps best indicated in Figures 2, 3 and 4. In these figures, time is plotted as abscissa and plate circuit current, plate voltage and grid voltage, respectively, are the ordinates. The time interval A-B represents a complete ignition cycle. This time interval necessarily varies with variation in the engine speed.

At point C, between A and B, the contact points of interrupter 24 are opened. The application thereupon of the negative voltage of battery 28 initiates a negative potential surge of approximately 100 volts, by virtue of the feed-back characteristics of windings 8 and 22 previously described. This is indicated in Figure 4. This negative potential surge serves to block the flow of electrons to the plate. When the plate current is thus reduced to a negligible flow, the collapse of the field of transformer 6 induces a voltage in secondary winding 10 which causes a spark to jump the gap of the plug selected by the distributor.

With my ignition system, I find it possible to get much more accurate timing than with ignition systems commonly in use today due to the elimination of arcing and the use of lighter contacts permitted in my system. It may be found desirable to substitute a trip device on the fly-wheel for the contactor, thereby eliminating gears with their associated lash and lost motion. This trip device may be magnetically or optically controlled, as desired.

A further advantage of my ignition system is that the current flowing through the contacts of the interrupter is so small that very little damage in the way of pitting and the like results to the contacts. Furthermore, I may increase the current flowing through the primary by merely adding tubes in parallel. This is a distinct advantage over present systems in that in present systems it is practically impossible to connect contactors in parallel.

I claim:

1. In combination, a transformer having primary and secondary windings, a spark gap in

- series circuit relation with the secondary winding, a source of electrical energy connected to one terminal of the primary winding, a three-electrode electric valve, an electrical connection from the other terminal of the primary winding to the anode of the valve, another electrical connection from the cathode of the electric valve to the energy source, a circuit interrupter connected to the energy source, an electrical connection from the circuit interrupter to the control grid of the electric valve applying a potential of a given polarity to the grid, and a source of electrical potential of the opposite polarity connected to the control grid circuit.
- 5 2. In combination, a transformer having primary and secondary windings, a spark gap in series circuit relation with the secondary winding, a source of electrical energy connected to one terminal of the primary winding, a three-electrode electric valve, an electrical connection from the other terminal of the primary winding to the anode of the valve, another electrical connection from the cathode of the electric valve to the energy source, a circuit interrupter connected to the energy source, an auxiliary primary coil connected to the circuit interrupter, an electrical connection from the auxiliary coil to the control grid of the electric valve to apply a potential of a given polarity to said grid, and a source of electrical potential of the opposite polarity connected to the control grid circuit.
- 10 3. An ignition system for internal combustion engines comprising a transformer having primary and secondary windings, a source of electric power connected to one terminal of the primary winding, a grid controlled vacuum tube, a connection from the other terminal of the primary winding to the anode of the tube, a connection from the cathode of the tube to the power source, a circuit interrupter connected to the power source, an auxiliary coil connected to the circuit interrupter, an electrical connection from the auxiliary coil to the control grid completing a control grid circuit in which a potential of one polarity is applied to the grid, and a source of electrical potential of the opposite polarity connected to the grid circuit.
- 15 4. In combination, a transformer having primary and secondary windings; a spark gap in series circuit relation with the secondary winding; a source of electrical energy connected to one terminal of the primary winding; a grid controlled vacuum tube; a connection from the other terminal of the primary winding to the anode of the tube; a connection from the cathode of the tube to the energy source; means for heating the tube cathode; a control circuit for the vacuum tube comprising the aforesaid energy source, a resistance connected to said source, a circuit interrupter connected to the resistance, an auxiliary primary coil connected to the circuit interrupter, a connection from the auxiliary coil to the control grid, and means for applying a control potential to the control grid upon opening of the circuit by the circuit interrupter whereby opening of the circuit interrupter makes the tube non-conductive causing collapse of the transformer field thereby inducing a voltage in the secondary winding which causes a spark to jump across the spark gap.
- 20 5. In combination, a transformer having primary and secondary windings, a spark gap in series circuit relation with the secondary winding, a source of electrical energy connected to supply energy to the primary winding of the

transformer, a grid controlled electric valve connected in the circuit including the energy source and the primary winding, a source of potential of one polarity for the grid of said electric valve, a source of potential of the opposite polarity for said grid, and means operating in timed relation with the requirements of the secondary winding for disconnecting the first source of grid potential.

6. The combination of claim 5, and means in the grid circuit for accelerating the reversal of polarity of the grid.

7. The combination of claim 5, and an auxiliary winding in said grid circuit, said winding being magnetically coupled with the transformer.

8. In an ignition system, a transformer having primary and secondary windings, an electric power source connected to the primary winding, a spark gap connected to the secondary winding, means in the power source connection to the primary winding to normally admit passage of electric current from the power source to the primary winding, control means for said last-mentioned means to permit blocking said current passage, and an auxiliary winding for said transformer connected to said control means.

9. In an ignition system, a transformer having primary and secondary windings, an electric power source connected to the primary winding, a spark gap connected to the secondary winding, electronic means in the power source connection to the primary winding to normally ad-

mit passage of electric current from the power source to the primary winding, control means for said last-mentioned means to permit blocking said current passage in timed relation with the requirements of the secondary winding circuit, and an auxiliary winding for said transformer connected to said control means.

10. An ignition system for internal combustion engines comprising a transformer having a primary and a secondary winding, a spark gap in series with the secondary, a source of electric power, an electronic tube having two main and one control electrodes, a series circuit connecting the source of power and the transformer primary to the two main electrodes of the tube, a separate biasing voltage and means connecting both the biasing voltage and the power source to the control electrode.

11. An ignition system for internal combustion engines comprising a transformer having a primary and a secondary winding, a spark gap in series with the secondary, a source of electric power, an electronic tube having two main and one control electrodes, a series circuit connecting the source of power and the transformer primary to the two main electrodes of the tube, a separate biasing voltage, means connecting both the biasing voltage and the power source to the control electrode and timing means connected to interrupt the connection of the power source to the control electrode.
